UNITED STATES PATENT OFFICE.

VICTOR A. STEWART, OF NEW YORK, N. Y.

PROCESS OF WATERPROOFING MOTION-PICTURE FILMS AND OTHER GELATINOUS SURFACES.

Application filed February 20, 1924. Serial No. 694,105.

To all whom it may concern:

Be it known that I, VICTOR A. STEWART, a subject of the King of Great Britain, and resident of New York city, in the county 5 of New York and State of New York, have invented certain new and useful Improvements in Processes of Waterproofing Motion-Picture Films and Other Gelatinous Surfaces, of which the following is a specification.

This invention relates to the process of exposing gelatinous surfaces, particularly having in mind the emulsion of exposed and developed motion picture film, to the action 15 of any suitable chemical vapors which have the property of converting the easily soluble colloid substance, into a new insoluble compound, thereby preventing injury to the film due to contact with moisture, water, etc.

I have found that by winding the film on a suitable reel with a porous material interwound therewith, for the purpose of separating the surfaces of the film and preventing their contact, and placing the reel 25 so wound in a gas tight chamber and exposing the same to the action of the chemical vapors for a predetermined time, I procure the desired result in a very expeditious, simple, economical and superior manner. I 30 may, for example, wind the film and a tape of cheese cloth into a roll, but do not limit the invention to the use of cheese cloth since other substances or materials may be employed for keeping the surfaces of the convolutions of the roll spaced apart to admit 35 the gas thereto.

One mode of carrying out the invention is illustrated in the accompanying drawings in which—

Fig. 1 is a side elevation of certain reels which may be employed to wind up the film and spacing tape.

Fig. 2 is a perspective view partly in section of a composite roll of film and tape such as may be produced by the apparatus shown in Fig. 1, and

Figs. 3 and 4 are longitudinal and transverse sectional views showing a gas tight chamber with the composite rolls mounted therein in a position for treatment.

As shown in Fig. 1 a roll 1 of motion picture film may be wound up upon a suitable reel 2 together with a tape 3 of cheese cloth, or equivalent porous or open textured material, whereby the convolutions of the 55 film of reel 2 are spaced apart by the tape.

A suitable number of the composite rolls thus formed are then placed within a gas tight chamber 4, for example, by stringing them on a rod 5 which rests upon suitable 60 brackets 6 in the end walls of the chamber.

The chemical vapors employed for treating the film will be projected into chamber 4 by means such as the perforated inlet and outlet pipes 7 and 8 shown in Figs. 3 and 4. 65

The above described apparatus is to be considered only as illustrative of one way of carrying out the invention and it is to be understood that the invention is in no way confined thereto.

I claim:

1. The method of subjecting exposed and developed photographic film to the action of chemical vapors to render insoluble the colloid substances on the film, which comprises winding up the film and an open textured spacing tape into a composite roll thereby to space apart the film convolutions, placing said reel in a gas tight chamber and projecting vapors into said chamber to act 70 upon the film surfaces through the medium of the tape.

2. The method of subjecting sheet material carrying exposed and developed photographic emulsions, to the action of chemical vapors to render insoluble the colloid substances in such emulsion, which comprises interposing open textured spacing strip material, between adjacent layers of such sheet material, placing the spaced apart 75 layers in a gas tight chamber and projecting vapors into said chamber to act upon the emulsion through the medium of such spacing strip material.

Signed at New York city, in the county 80 of New York and State of New York, this 19th day of February, A. D. 1924.

VICTOR A. STEWART.
